CLEAVER

Marshall Thomas Joseph Garlinger,
San Jose, Calif.Application June 13, 1936, Serial No. 85,088
Renewed July 18, 1938

14 Claims. (Cl. 111—5)

The present invention relates to improvements in cleavers or subsoil plows and its principal object is to provide a cleaver for use in connection with cable laying apparatus and constructed in such a manner as to perform its function with the greatest efficiency while at the same time being easily accessible for repair and exchange purposes.

The present application is a continuation in part of my application Serial Number 61,387, filed January 29th, 1936, on a Machine for laying cable, pipe and the like and is intended to cover the specific features of a cleaver or subsoil plow described in said application, together with certain modifications thereof.

More particularly it is proposed to provide a cleaver of this character that is rugged in construction, is streamlined from front to rear so as to offer little obstruction and to gradually spread the ground surface for forming a crevice and in which the cable laying pipe is supported in such a manner that it makes no contact with the soil and is completely protected from abrasion by the soil and rocks or other cutting agencies contained in the soil.

A further object of the invention is to make the cleaver in two parts one of which is movable relative to the other so as to give easy access to a blade confined between the two parts.

A further object of the invention is to provide means for holding the movable part of the cleaver in an inactive position so that the repair men not only have ample room for repairing, adjusting or replacing of the blade but may also perform these operations in perfect safety and without any danger of the movable section falling back into place.

A further object of the invention is to provide a structural arrangement particularly well adapted for the purposes outlined, with braces and fastening means disposed in such a manner that the cleaver when assembled becomes a strong, compact unit capable of meeting all stresses and strains to which an apparatus of this character is normally subjected.

Further objects and advantages of my invention will appear as the specification proceeds.

The preferred form of my invention is illustrated in the accompanying drawing in which Figure 1 shows a vertical longitudinal section through my cleaver,

Figure 2 a horizontal section taken along line 2—2 of Figure 1,

Figure 3 a side elevation showing a portion of the cleaver in locked elevated or inactive position,

Figure 4 a modification of my cleaver; and Figure 5 a vertical section along line 5—5 of Fig. 4.

While I have shown only the preferred form of my invention I wish to have it understood that various changes or modifications may be made within the scope of the claims hereto attached without departing from the spirit of the invention.

In its general characteristics my cleaver 1 is 10 a narrow vertical body tapering to an inclined cutting edge in front and provided with a horizontal cutting edge at the bottom. It is made in two sections 2 and 3, the former being a box-like structure with approximately parallel side 15 walls 4 converging toward the front as at 5, an inclined rear wall 6, a bottom wear plate 7 and a front wall which is vertical in its upper portion as at 8 and inclined in its lower portion as at 9 to form a seat for the blade 10 which is 20 bolted thereto by the bolt 11. The blade is provided with a plurality of bolt holes so that it may be advanced as the cutting edge wears off.

The inclined portion 9 is continued through the body to the rear wall 6 to brace the cleaver 25 and to form a bearing for the feed pipe 12 which extends obliquely through the cleaver and terminates with a flared end at the bottom of the rear wall of the cleaver. The front wall of the section 2 has an undercut 13 over the inclined 30 portion 9 to receive the rear end of the blade 10.

The purpose of the feed pipe is explained in the parent application. Suffice it to say, in this connection, that it serves the general purpose of feeding a cable or the like into the ground at 35 the rear of the cleaver so that the cable occupies a position in the bottom of the crevice made by the advancing cleaver.

The section 3 forms the front of the cleaver. It has an inclined front edge formed with a 40 groove adapted to receive the root-cutter 14 which is held in place by rivets 15. It is pivoted on the pin 16 which latter is supported in a flange or bar 17 depending from the feed pipe 12 and section 2 of the cleaver, and when in 45 active position its bottom edge rests on the blade 10. It is firmly held in place by an eye bolt 18 pivoted to the pin 19 extending transversely through this section and bolted to a cross-rib 20 provided in the bottom of the first section 2. 50 Blade 10 is further clamped in place by the wedging action of section 3. The inclined seat 9 and the blade are suitably apertured as at 21 to allow the bolt to move when the front section is swung upward on its pivot 16. The flange 17 is pro- 55

vided with an aperture 22 below the pivot 16 so that when the front section is swung upward, a bolt 22' may be inserted through the aperture as shown in Figure 3 for holding the front section 5 in raised position. Any other suitable locking arrangement may be substituted for the means here described.

The rear wall of the front section 3 is grooved as shown at 23 to fit over a tongue 24 projecting 10 from the vertical front face of the main body section 2, whereby the two sections are automatically brought into alinement when the front section is dropped back into active position.

It will be noted that in this manner the front 15 section, upon loosening of the eye bolt 18, either at the bottom or at the eye, may be swung upward and locked in raised position so as to give ready and easy access to the blade 10 for adjustment, repair or substitution of a new blade. Since 20 the front section 3 is subjected to considerable wear, the entire section, as well as the root-cutter blade 14, may also be easily removed, repaired or replaced. This will increase the operating efficiency and economy of the entire machine.

25 A supporting post 25 rises from the cleaver and is used for supporting the cleaver relative to a vehicle described in the parent application.

A groove 26 fits the flat sides of the bolt head 11. The groove prevents the bolt from turning 30 when the nut is tightened and also helps to brace the front sections 3 when wedged tightly against the blade 10. The wedging action of the front section is obtained by the angular position of bolt 18 with respect to the corner of front section 3 35 through which the bolt extends.

It is understood that instead of bolt 11 holding blade 10 in place, the same result can be accomplished by the placing of transverse teeth 27 and a longitudinal key or spline 28 on the lower face 40 of blade 10 and corresponding transverse teeth 29 and a keyway 30 on the upper inclined face of section 2, the above mentioned wedging and clamping action of the front section 3 thus holding blade 10 firmly in place. To allow for wear 45 of blade 10, it is merely necessary to loosen the nut on the eye bolt 18 and to advance the blade to the desired position. The nut on the eye bolt is then tightened. This is a valuable time saving and safety element of my invention.

50 While shown as a bolt and described as a bolt or teeth and key for holding blade 10 in place, it is understood that this is for purposes of illustration only and that any suitable means may be provided for holding the blade 10 in place.

55 I claim:

1. A cleaver comprising a body portion having a hollow rear section and an inclined front face adapted to receive a blade thereon, the inclined front face extending through the rear section, 60 and a feed pipe supported in said extension.

2. A cleaver comprising a body portion having a hollow rear section and an inclined front face adapted to receive a blade thereon, the inclined front face having an extension passing through 65 the hollow rear section, a feed pipe supported in said extension and having a flange suspended therefrom and a front section hinged to the flange and adapted to overlie a blade disposed on the front face.

70 3. A cleaver comprising a body portion having a hollow rear section and an inclined front face, a blade secured to the front face, an overhang projecting from the rear section to form a blade receiving recess with the front face, an extension 75 of the front face projecting through the hol-

low rear section, a feed pipe secured in said extension and having a flange suspended therefrom above the rear section, a front portion hinged to the flange and adapted to overlie the blade and a bolt hinged to the front portion, the blade and the front face having apertures permitting the bolt to pass therethrough and the body portion having means engaging said bolt for clamping the front portion upon the blade. 5

4. A cleaver for a machine of the character 10 described comprising a body section, a front section and a blade interposed between the two sections, the front section being hinged and anchored to the body section so as to allow the front section to be swung away from the blade for facilitating access to the latter. 15

5. A cleaver for a machine of the character described comprising a body section, a front section, a blade interposed between the two sections, the front section being hinged relative to the 20 body section so as to allow the front section to be swung into a position to clear the blade for facilitating access to the latter and means for holding the front section in blade-clearing position.

6. A cleaver for a machine of the character 25 described comprising a body section, a front section, means for movably securing the front section to the body section, a blade interposed between the two sections, the front section being movable into a position to clear the blade for 30 facilitating access to the blade, and means cooperating with the front section for holding the front section in blade-clearing position.

7. A cleaver for a machine of the character 35 described comprising a body section, a front section, a blade interposed between the two sections, the front section being hinged and anchored to the body section and being swingable into elevated position above the blade to clear the latter for facilitating access to the blade and means for 40 clamping the front section upon the blade.

8. A cleaver for a machine of the character 45 described comprising a body section, a front section, a blade interposed between the two sections, the front section being hinged and anchored to the body section and being swingable into elevated position above the blade to clear the latter for facilitating access to the blade and means for holding the front section in elevated position above the blade.

9. A cleaver comprising a body portion having 50 an inclined front face adapted to receive a blade thereon and an overhang over the rear portion of said face to form a blade receiving recess therewith, a blade disposed on said face and projecting into said recess, the blade and the inclined face having interlocking portions to prevent the blade from slipping relative to said face, and means for securing the blade to said face. 55

10. A cleaver comprising a body portion having 60 an inclined face adapted to receive a blade thereon, a blade disposed on said face, the blade and the inclined face having interlocking portions to prevent the blade from slipping relative to said face, and means clamping the blade upon 65 said face.

11. A cleaver comprising a body portion having 70 a hollow rear section and an inclined front face, a blade secured to the front face, an extension of the front face projecting through the hollow rear section, a feed pipe secured in said extension, a front portion adapted to overlie the blade, a bolt hinged to the front portion, the blade and the front face having apertures permitting the bolt to pass therethrough and means 75

engaging said body portion and bolt for clamping the front portion upon the blade.

12. A cleaver comprising a body portion having an inclined front face, a blade secured to the front face, a front portion adapted to overlie the blade, a bolt hinged to the front portion, the blade and the front face having apertures permitting the bolt to pass therethrough and means engaging said body portion and bolt for clamping the front portion upon the blade.

13. A cleaver comprising a body portion having an inclined blade-receiving face, a blade disposed on said face, a front portion hinged and anchored above said face and having an inclined

15 lower end to bear against the blade, a bolt hinged to the front portion, the blade and inclined face

having apertures permitting the bolt to pass therethrough and means engaging said body portion and bolt for clamping the front portion upon the blade.

14. A cleaver comprising a body having a 5 blade-receiving face, a blade disposed on said face, a bolt securing the blade to said face having a head arranged above the blade, a front section hinged and anchored above said face and being movable into position to bear against the 10 blade, the front section having a recess therein to engage the bolt head to hold the latter against turning when the front section contacts the blade, and means clamping the front section upon the blade.
